(57) **CLAIM**

The ornamental design for an elongated ant bait station as shown and described.

DESCRIPTION

FIG. 1 is a top perspective view of the elongated ant bait station showing the present design.

FIG. 2 is a top view thereof.

FIG. 3 is a bottom view thereof.

FIG. 4 is front view thereof.

FIG. 5 is a rear view thereof.

FIG. 6 is a left side view thereof.

FIG. 7 is a right side view thereof; and,

FIG. 8 is a top perspective view of the elongated ant bait station mated with a second ant bait station.

The portions of the design shown in broken lines being for the purpose of illustrating environment only and form no part of the claimed design.
